UNITED STATES PATENT OFFICE.

ALFRED ERASMUS GEOFFREY MACCALLUM, OF WANDSWORTH, LONDON, ENGLAND.

GRINDING MILL.

Application filed November 19, 1928, Serial No. 320,473, and in Great Britain September 5, 1927.

This invention relates to grinding mills for paint and like materials in which a number of grinding rollers are arranged with their axes parallel and in which the material 5 to be ground is passed between one or more pairs of rollers and is subsequently caused to pass between a roller and a fixed grinding bar to complete the grinding operation.

The object of the present invention is to 10 provide an improved method of mounting pairs of grinding rollers and to provide improved means for adjusting the positions of these rollers relatively the one to the other.

According to the invention a four roll 15 grinding mill is provided wherein the members of a lower pair of rollers rotate about fixed axes and co-operate with a pair of rollers adjustable vertically as a pair relatively to the lower rollers and adjustable relatively 20 the one to the other.

According to another feature of the invention an upper pair of rollers is adjustable relatively to the lower pair rotatable about 25 fixed axes in such a manner that the axes of the upper rollers move during adjustment through paths concentric with the axes of the respective lower rollers.

Reference will now be made to the accompanying drawings which illustrate by way of 30 example a four roll grinding mill constructed according to the invention and in which:—

Figure 1 is an end elevation of the mill and

35 Figure 2 is a sectional elevation of one of the end supports taken on the line 2—2 of Figure 1.

In the form illustrated four rollers are arranged so that two rollers 1 and 2 rotate 40 about axes in a plane above that of the axes of the lower pair of rollers 3 and 4. The upper rollers are in engagement the one with the other and each engages one of the lower rollers so that the material under treatment 45 is caused to descend between the upper rollers and passes between the upper and lower rollers whilst the final grinding is imparted by grinding bars 5 held in adjustable relationship with the lower rollers 3 and 4 in 50 any suitable manner, and the ground product is removed by scrapers 37 and collected in trays 38. The lower rollers 3 and 4 rotate on shafts 6 and 7 carried in fixed bearings 55 mounted in end frame members 8 and the upper rollers 1 and 2 are carried in bearings,

hereinafter described, mounted in frames 9 mounted in guides formed in the main frame members 8 so as to be capable of vertical adjustment.

To the underside of each frame 9 and at 60 the centre thereof is connected a rod 10 the lower end of which has screw threaded engagement with the central boss of a worm wheel 11, this worm wheel being engaged by a worm 12 mounted on a horizontal shaft 13 65 carried in bearings on the frame work 8 and provided with a hand wheel 14 for manual operation. The vertically slidable frame 9 is slotted as shown at 15 to accommodate bearings for the spindles 16 of the upper 70

pair of rollers 1 and 2. Each bearing consists of fixed members 17 in which are slidably mounted bearing members 18 carrying the ends of the shaft 16. The bearing members 18 are formed externally and the bearing members 17 are formed internally with bearing surfaces concentric with the centres of rotation of the lower rollers 3 and 4, respectively, and the two bearing members 18 are urged apart by plungers 19 between 75

80 which is disposed a spring 20, the plungers 19 and spring 20 being housed in a member

21 of the sliding frame 9 which extends upwards between the bearings of the rollers

1 and 2.

85 The bearings for the upper rollers are held in position by a plate 22 which is secured by bolts 23 into the upper portion of the sliding frame 9 and upon the plate 22 is mounted a bearing 24 through which passes a shaft 25 90 which is so connected to the bearing that it is capable of rotational but not longitudinal movement with respect thereto. The shaft 25 is provided at one or both ends with a hand wheel or wheels 26 and is also provided at its ends with oppositely screw threaded portions 27 and 28. These screw threaded portions engage sleeves 29 to which are pivotally connected links 31 whose lower ends

95 are pivotally mounted to the upper portion 100 of the frame work 8 at 32. The links 31

are pivoted between their ends to the outer

ends of plungers 33 which are freely slidable

through openings in the upper portion of

the frame work 8 and enter sockets 34 in the

sliding frame work 9 in which plungers 35

are slidably mounted, the inner ends of these

plungers 35 engaging the outer surfaces of

the bearing elements 18. To allow for vertical

adjustment of the frame 9 the inner ends 110

of the plungers 33 are tapered as shown at 36 and are of such dimensions as to enter loosely the sockets 34. The mechanism above described is duplicated so that the upper rollers are adjustable at each end.

With the arrangement above described the upper rollers 1 and 2 can be adjusted towards or away from one another by operation of the hand wheel 26, movement of 10 which in one direction forces the plungers 35 towards each other whilst in the opposite direction the pressure on these plungers is slackened to allow the spring 20 to operate and move the bearings apart. The shape 15 and mounting of the bearing members 18 ensures that in all adjustments the axes of the rollers 1 and 2 move in paths concentric with the axes of rotation of the rollers 3 and 4 respectively.

20 I claim:—

1. A grinding mill comprising a framework, a pair of lower rollers rotatable in said framework on fixed axes, a frame vertically adjustable in said framework, a pair 25 of upper rollers for engagement, respectively, with said lower rollers, and a pair of bearings for the opposite ends of each of said upper rollers, said pairs of bearings being movable in said frame toward and away 30 from one another in arcs concentric, respectively, with the axes of the lower rollers.

2. A grinding mill according to claim 1, including means for vertically adjusting the frame and means for moving the pairs of 35 bearings toward and away from one another.

3. A grinding mill comprising a framework, a pair of lower rollers rotatable in said framework, a pair of upper rollers to respectively engage said lower rollers, a frame vertically adjustable in said framework and having two oppositely directed pairs of guideways, each pair of which is curved on an arc concentric with the axis of rotation of one of said lower rollers, and a 45 pair of bearings for the ends of each of said upper rollers, the pair of bearings for each upper roller being movable toward and away from the other pair of bearings in a pair of guideways. 50

4. A grinding mill according to claim 3, comprising means tending to move the pairs of bearings away from one another and means for moving said bearings toward one another and securing them in adjusted position. 55

5. A grinding mill according to claim 3, comprising means tending to move the pairs of bearings away from one another, means for moving said bearings toward one another and securing them in adjusted position, and means for vertically adjusting said frame. 60

6. A grinding mill according to claim 1, including means for vertically adjusting the frame toward and away from the lower rollers. 65

In testimony whereof I have hereunto set my hand.

ALFRED ERASMUS GEOFFREY MacCALLUM.
